Sherwood C. Ide, Gowanda, N. Y.

Application January 4, 1937, Serial No. 66,888

To all whom it may concern:

Be it known that I, Sherwood C. Ide, a citizen of the United States, residing at Gowanda, in the county of Cattaraugus and State of New York, have invented a new, original, and ornamental Design for a Game Apparatus, of which the following is a specification, reference being had to the accompanying drawing, forming part thereof.

The figure is a perspective view of a game apparatus showing my new design.

The side of the apparatus not shown is identical in appearance with the side illustrated.

The printed matter appearing at the top part of the figure is merely representative and does not form part of the design per se.

I claim:

The ornamental design for a game apparatus, as shown and described.
